UNITED STATES PATENT OFFICE.

HENRY L. F. TREBERT, OF SYRACUSE, NEW YORK, ASSIGNOR TO
E. C. STEARNS.

BICYCLE FORK-CROWN.

SPECIFICATION forming part of Letters Patent No. 659,187, dated October 2, 1900.

Application filed July 16, 1900. Serial No. 23,853. (No model.)

To all whom it may concern:

Be it known that I, HENRY L. F. TREBERT, of Syracuse, in the county of Onondaga, in the State of New York, have invented new 5 and useful Improvements in Bicycle Fork-Crowns, of which the following, taken in connection with the accompanying drawings, is a full, clear, and exact description.

My invention is a strong, simple, and economical fork-crown in which the parts are strongly reinforced, securely locked in position, and easily reached for brazing.

My invention will be understood by reference to the accompanying drawings, in which 15 the same reference-numerals indicate the same parts in all the figures.

Figure I shows my new form of fork-crown partially in elevation and partially in vertical section. Fig. II is a plan of the detached 20 finishing-plate. Fig. III is a plan of the crown-plate detached. Fig. IV is a plan of the lower or locking plate. Fig. V is a horizontal cross-section on line V V of Fig. I, showing the relation of this locking-plate to the fork side 25 and locking-piece. Fig. VI is an elevation of the inner face of the upper end of a fork side. Fig. VII is a corresponding elevation of the locking-piece.

In the figures, 1 indicates the steering-post; 30 2, a tubular reinforcing-piece arranged on the exterior thereof and taking the place both of the reinforcement commonly inserted in the interior and of the outside finishing-ferrule.

3 is the crown-plate, perforated at 4 to fit 35 over this reinforcing-piece and at 5 to receive the upper ends of the fork sides 6 6, slotted at 7 7 to receive the lips 8 8 of the lower or locking plate 9, perforated at 10 to receive the lower end of the steering-post and 40 reinforcing-piece, and having its ends fitting within fork sides, as best shown in Fig. VI. These are slotted at 11 11 and provided with tips 12 12, respectively, to receive the inner edges 13 13 and to fit the outer slot 14 of the 45 locking-piece 15, formed to fit the upper end of the fork side. This locking-piece is set in position after the other parts are assembled, locking them securely in position and reinforcing the upper ends of the fork sides. The 50 parts are then securely and easily brazed,

and there is preferably added the finishing-plate 16, having the integral cone 17 and the flange 18, fitted over the edge of the crown-plate. By this the fork-crown is neatly finished, the ends of the fork sides and joints 55 being covered and the cone provided for the ball-bearing. The reinforcing-piece 2 may be turned down on a bevel, if desired.

Having thus fully described my invention, what I claim, and desire to secure by Letters 60 Patent, is—

1. In combination in a bicycle fork-crown, the steering-post, an exterior reinforcing-piece fitted to the lower end thereof, a crown-plate fitted thereto and perforated at its ends 65 to receive the fork sides, the fork sides slotted on their inner faces, a locking-plate fitted to said slots and to the lower ends of the post and locking-pieces fitted within the fork sides and engaging with the ends of said locking- 70 plates.

2. In combination in a bicycle fork-crown, the steering-post, a tubular exterior reinforcing-piece fitted to the lower end thereof, a crown-plate centrally perforated to fit over 75 the reinforcing-piece, and perforated at the ends to receive the fork sides, the fork sides slotted on their inner faces, a locking-plate having lips fitted to said slots and formed with inclined slots between the lips and the 80 main portion of the locking-plate, tips on the ends of said lips, locking-pieces fitting within the upper end of the fork sides and formed with slots on their outer faces to receive said locking-plate tips. 85

3. In combination in a bicycle fork-crown, the steering-post, a tubular exterior reinforcing-piece fitted to the lower end thereof, a crown-plate centrally perforated to fit over 90 the reinforcing-piece, and perforated at its ends to receive the fork sides, the fork sides slotted on their inner faces, a locking-plate having lips fitted to said slots and formed with inclined slots between each lip and the main portion of the locking-plate, tips on the 95 ends of said lips, locking-pieces fitting within the upper end of the fork sides and formed with slots on their inner faces having edges to fit said locking-plate slots and with slots on their outer faces to receive said locking- 100

tips, and a finishing-plate having an integral cone to surround the steering-post and with a marginal flange to cover the top plate.

4. In combination in a bicycle fork-crown, 5 the steering-post, a crown-plate fitted to the lower end thereof and fitted to receive at its ends the upper ends of the fork sides, the fork sides fitted thereto and slotted on their inner faces, a locking-plate arranged below 10 and parallel to the crown-plate, fitting the lower end of the steering-post and having ends fitted to the slots in the fork sides.

5. In combination in a bicycle fork-crown, 15 the steering-post, a tubular reinforcing-piece fitted outside its lower end and having a beveled upper end, a crown-plate centrally perforated snugly to fit said reinforcing-piece and perforated at its ends to receive the fork sides, the fork sides having their upper ends 20 fitting said perforations and slotted on their inner faces substantially on a plane with the lower end of the steering-post, a locking-plate substantially perforated to fit the lower

end of the reinforcing-piece around the steering-post and having lips on its ends fitted to 25 said slots in the inner faces of the fork sides, said ends being formed with inclined slots between the lip on each side and the main portion of the locking-plate, tips on the ends of 30 said lips, locking-pieces fitting within the upper end of the fork sides formed with slots on their inner faces, the edges thereof being adapted to fit the locking-plate slots and with slots on the lower portion of their outer faces fitting said locking-plates, tips, tubes, and a 35 finishing-plate formed with an integral cone surrounding the steering-post and reinforcing-piece and with a downwardly-depending marginal flange to cover the top plate.

In testimony whereof I have hereunto 40 signed my name.

HENRY L. F. TREBERT. [L. S.]
